UNITED STATES PATENT OFFICE.

GEORGE POLHAMUS, OF TOLEDO, OHIO.

CARRIER FOR PAILS AND THE LIKE.

Application filed June 23, 1926. Serial No. 117,906.

This invention relates to devices for carrying pails, buckets, or the like, but more particularly to such device which is useful in carrying paint pails for preventing spilling of the contents and enabling the pail to be readily carried and supported in a convenient manner.

Objects of this invention are to provide a simple and efficient carrier for pails, buckets and the like, which may be cheaply manufactured, which is sturdy in construction and which will serve effectively for carrying pails or buckets without liability of spilling the contents. Other objects and advantages 15 will hereinafter appear.

This invention is shown by way of illustration in the accompanying drawings, in which:

Fig. 1 is a side elevation of the carrier 20 attached to a pail; Fig. 2 is a view similar to Fig. 1 with carrier turned at right angles; and Fig. 3 is a section on the line 3—3 of Fig. 2.

The illustrated embodiment of the invention comprises a carrier consisting of a pair of U-members 1 and 2 which, in this instance, are disposed at substantially right angles to each other, and which may be of strap iron or other suitable material. The legs 30 of the U-member 2 are shorter than the legs of the U-member 1, and are inclined inwardly towards each other, the opposite ends of these legs being provided with outwardly turned portions 3. The U-members 35 1 and 2 are adapted to receive a pail 4 and the outwardly turned portions 3 enable the pail to be forced into position between the legs of the U-member 2 and cam these legs outwardly to a slight extent, these legs being 40 sufficiently resilient yieldingly to engage the adjacent sides of the pail 4, and frictionally to hold the same in place. Any suitable means may be provided for securing the U-members 1 and 2 together, and in this instance a rivet 5 is employed for holding the parts in assembled relation, and although, both the U-members are disposed at substantially right angles to each other it will be understood that this position may be 45 changed without departing from the spirit of the invention.

Formed on the ends of the legs of the U-members 1 are outwardly inclined portions 6, to which is pivoted a bail 7. This ar-

rangement has been found decidedly advantageous, in that, when the bail is lifted the outwardly inclined portions 6 are drawn inwardly against the adjacent sides of the pail, and frictionally to engage these sides for holding the pail securely in position and prevent the pail coming loose from the carrier. The inclined or curved portions extend for a distance outwardly of the legs of the U-member 1, and accordingly upon lifting of the bail have an appreciable inward movement so as to effectively grip the pail. Further, due to the divergent relationship between the parts 6, the latter are automatically spread upon being engaged with the bottom of the pail to thus apply 70 the device to the pail without manual manipulation of the parts 6. Formed centrally of the bail 7 is a hook 8, and this hook may be formed by twisting the end portions of the bail into the shape shown in the drawing. It is obvious that the hook 8 serves 75 as a suspending means for the carrier.

It is to be understood that the above description is given by way of illustration and not of limitation, and numerous changes in 80 details of construction, arrangement and choice of material may be effected without departing from the spirit of the invention, especially as defined in the appended claim.

What I claim as new and desire to secure 85 by Letters Patent is:

A pail carrier composed of a pair of U-shaped members having their bases secured together to form a seat for the pail bottom and to provide a series of legs which latter 90 engage the pail sides, the upper free ends of each of the legs of one of the members being extended outwardly at an incline for a distance so as to have a relatively divergent relationship thereby to effect automatic 95 outward spreading upon engagement with the bottom of a pail in applying the device to the pail, and a carrying bail secured at its ends to the free extremities of the inclined portions of the legs of said members 100 whereby upon lifting of the bail, the inclined portions will be moved inwardly so that the inner ends thereof fulcrum against the top of the pail thereby to firmly grip the latter.

In testimony whereof I have hereunto 105 signed my name to this specification.

GEORGE POLHAMUS.
